CIRCUIT BREAKER

Kurt Wulsten, Berlin-Charlottenburg, Germany,
assignor to Westinghouse Electric & Manufacturing Company, East Pittsburgh, Pa., a corporation of Pennsylvania

Application September 16, 1937, Serial No. 164,142
In Germany September 11, 1936

18 Claims. (Cl. 200—88)

The invention relates to electrical circuit controlling devices, in general, and more particularly, to circuit breakers of the type which are manually operable to open and to close the circuit and automatically operable to open the circuit in response to predetermined overload or fault conditions, and which are used for controlling lighting and moderate power industrial feeder circuits.

5 Due to the inter-connection of a large number of circuits in such applications, a considerable burden is placed on the individual circuit breakers since very large amounts of power may be fed into a short circuit or other fault condition.

10 The circuit breaker involved must be capable of interrupting large amounts of power in the shortest possible time. Heretofore reliance has been placed on snap-acting operating mechanisms and arc extinguishing means to shorten

15 the time of circuit interruption following occurrence of the fault condition. In most instances, however, the necessary contact pressure in the closed position of the breaker has been obtained by the resilient mounting of at least one of the

20 contacts, and this arrangement has the inherent disadvantage that the time required to relax the resilient means before the contacts separate materially increases the time required for circuit interruption. Furthermore, as the contact pressure approaches zero value, the contacts may

25 become welded together, thus preventing opening of the circuit.

It is accordingly an object of the invention to provide an improved circuit breaker which is operable to effect circuit interruption in a shorter period of time than has heretofore been achieved.

Another object of the invention is the provision of a circuit breaker embodying an improved actuating and coacting tripping means for effecting a very rapid circuit interruption.

The general arrangement for carrying out this feature of the invention consists in providing a spring directly engaging the switch member for biasing the same to open position, an actuating means for opening and closing the switch member which includes a spring means for securing pressure engagement of the contacts when the breaker is closed, and a trip member normally connecting the actuating and contact pressure

45 securing spring means to the switch member, which is operable in response to predetermined conditions to disconnect the actuating and contact pressure securing spring means from the switch member to permit opening of the same by its biasing spring. In addition, an improved

arc-extinguishing structure is provided for quickly extinguishing the arc drawn between the contacts.

In addition to the previously mentioned requirements, for a circuit breaker to be commercially successful, it must be safe in operation, compact in structure, inexpensive to manufacture and its parts readily accessible for servicing.

Another object of the invention is the provision of an improved circuit breaker which will satisfactorily meet all of the previously mentioned requirements.

Another object of the invention is the provision of a circuit breaker embodying an improved arc-extinguishing structure.

Another object of the invention is the provision of a circuit breaker in which the operating mechanism and contact means are assembled as a unit, removably mounted on the breaker base, and readily accessible for servicing.

Another object of the invention is the provision of a circuit breaker in which the insulating base for supporting the breaker is formed to provide an enclosed interrupting chamber for the contacts, thus eliminating the necessity of a separate structure for this purpose.

The novel features that are considered characteristic of the invention are set forth in particular in the appended claims. The invention itself, however, both as to structure and operation, together with additional objects and advantages thereof, will best be understood from the following detailed description of several embodiments thereof when read in connection with the accompanying drawings, in which:

Figure 1 is a side view, partly in section and partly in elevation, of the circuit breaker embodying the features of the invention;

Fig. 2 is a vertical sectional view of the circuit breaker illustrated in Fig. 1;

Fig. 3 is a plan view of the circuit breaker with the cover removed;

Fig. 4 is an end view partly in elevation and partly in section, of the circuit breaker;

Fig. 5 is a plan view of the base of the circuit breaker;

Fig. 6 is a plan view of one of the arc-extinguishing plates;

Fig. 7 is a plan view of the winding spool for the electromagnetic blowout and trip means;

Fig. 8 is a diagrammatic view illustrating the electrical connection of the windings of the aforementioned electromagnetic means to the contacts of the breaker;

Fig. 9 is a schematic view of a modification of the invention;

Fig. 10 is a schematic view showing the contact means and actuating means of the embodiment shown in Fig. 1 in the manually open position of the breaker;

Fig. 11 is a view similar to Fig. 10 showing the contact means and actuating means in the manually closed position of the breaker;

Fig. 12 is a view similar to Fig. 10 showing the position of the parts immediately following release of the trip latch during a tripping operation of the breaker; and

Fig. 13 is a horizontal sectional view of the circuit breaker taken substantially on the line XIII—XIII of Fig. 2.

Referring to the drawings, particularly Figs. 1 through 4 thereof, the circuit breaker illustrated comprises, in general, relatively movable contact means indicated generally at 15, actuating means therefor indicated generally at 17, a trip latch member 19, which serves to releasably connect the actuating means to the contact means, an electromagnetic means indicated generally at 21 for blowing out the arc formed during circuit interruption and for actuating the latch member 19 to trip the breaker open in response to predetermined conditions, and a thermal trip element 23 which is also operable to actuate the latch member 19 to trip the breaker. The aforementioned elements are all assembled together and to a main frame 25 of inverted U-shape, to form a unitary breaker assemblage which is adapted to be removably mounted on a base 27 of insulating material. A cover 29 also of insulating material is provided for enclosing and protecting the unitary breaker assemblage, the cover being secured to the assemblage by means of a screw 31 which engages a threaded opening provided therefor in the upper portion of the frame 25.

The contact means of the breaker, as shown in Figs. 2 and 10 to 12, comprises a pair of spaced stationary contacts 33 and a movable bridging contact 35. The stationary contacts 33 are carried by bolts 37 which engage internally threaded conducting sleeves 38 embedded in an insulating body 39 which forms a winding spool for the windings of the electromagnetic means. The movable bridging contact 35 is secured to the lower end of an operating rod 41 which is mounted for vertical sliding movement in a vertical opening provided therefor in the insulating body 39. The upper end of the operating rod 41 is pivotally connected by means of a pin 43 to a contact lever 45 which is pivotally mounted on a main pivot pin 47 carried by the frame 25. The operating rod 41 and movable bridging contact 35 carried thereby are biased in a downward direction to open position by means of a coil compression spring 49 surrounding the rod 41. The upper end of the spring engages a vertical insulating sleeve 42 provided in the core of the electromagnetic means, while the lower end thereof engages an insulating sleeve 51 mounted on the lower portion of the rod 41.

The actuating means for the breaker comprises, in general a manually operable handle 53, a pair of toggle links 55 and 57, a pair of pivoted bell crank levers 59 and a spring means 61 for securing a pressure engagement of the contacts in the closed position of the switch. The operating handle is pivotally mounted on the main pivot pin 47 and is biased in a clockwise direction by a spring 54. The handle 53 is provided with an operating knob 63 which projects through a suit-

able opening 65 provided therefor in the cover 29. The toggle link 55, which is U-shaped, is also pivotally mounted at one end on the main pivot pin 47 and its legs are provided with angular extensions 67 which carry a transverse pin 69. The pin 69 extends through a slotted opening 71 formed in the handle 53, the slotted opening 71 and the pin 69 forming a lost motion coupling means between the handle 53 and the toggle link 55. The lower toggle link 57 which is U-shaped, is pivoted at its upper end to the lower end of the toggle link 55 by means of a knee pivot pin 73. The two bell crank levers 59 which are mounted on opposite sides of the frame 25, are pivoted to the side walls of the main frame by 15 means of the pivot screws 75 (Fig. 1). The right-hand arms of the bell crank levers 59 are secured for movement together by a transverse pivot pin 77 and this pin 77 engages slotted openings 79 provided therefor in the legs of the lower 20 toggle link 57. The bell crank levers 59 are thus coupled at their one ends to the lower toggle link 57.

The contact pressure securing spring means 61 consists of a coil tension spring, the upper end 25 of which is secured to the transverse pivot pin 77, the lower end thereof being secured to the right portion or lower end of the toggle link 57, as shown in Fig. 6.

The actuating means of the circuit breaker is 30 adapted to be releasably connected to the contact means and operating rod 41 by means of the floating trip latch member 19. The latch member 19 comprises a plate 81 of magnetic material to which is secured a transverse pin 83 and a 35 latch plate 85. The opposite ends of the transverse pin 83 engage vertical slots 87 provided therefor in the side walls of the frame 25 so that the latch member 19 is mounted for vertical movement. The left-hand ends of the bell crank 40 levers 59 are provided with horizontal slots 89 in which the extended end portions of the transverse pin 83 engage to couple the bell crank levers 59 to the latch member 19. The latch member 19 is biased in a clockwise direction about the pivot 45 pin 83 by means of the weight and position of the latch plate 85 and/or a suitable spring means (not shown), and the free end of the lever 45 is adapted to normally engage the upper edge of the latch plate 85 as shown in Fig. 2. It will thus 50 be seen that the latch member 19 normally couples the actuating means 17 to the contact operating lever 45 and operating rod 41. The magnetic portion of the latch member 19 cooperates with the electromagnetic means 21 so that when 55 a high magnitude overload or short circuit condition occurs in the circuit controlled by the breaker, the latch member 19 is rotated in a counter-clockwise direction, as viewed in Fig. 2, to release the contact lever 45 and permit opening of the contact means by the biasing spring 49, as will be hereinafter described.

For effecting automatic opening of the contact means of the breaker in response to lower magnitude overloads of predetermined duration, there 65 is provided the thermally responsive trip element 23 which consists of a strip of bimetallic material secured at its upper end to the frame 25 and connected in circuit with the contact means of the breaker. The lower free end of the trip 70 element 23 is provided with an adjustable screw 88 for engaging and moving the lower end of the latch member 19 when the trip element is heated a predetermined amount in response to an overload condition. The trip element 23 is adapted 75

to flex toward the actuating mechanism when heated by overloads of predetermined magnitude and duration to engage and move the latch member 19 in a counter-clockwise direction to effect release of the contact lever 45 and opening of the contact means of the breaker.

The electromagnetic means for blowing out the arc drawn between the contacts during circuit interruption and for actuating the trip member 19 in response to high magnitude overloads and short circuit conditions comprises a core 90 of magnetic material, a pair of spaced pole pieces 91 and a pair of separate windings 93 only one winding being shown in Fig. 2. The core member 90 is mounted within and extends through a hollow hub portion 95 (Figs. 7 and 13) of the insulating body 39 and its ends are secured to the pole pieces 91 which are disposed on opposite sides of the body 39. The insulating body 39 is provided with a central portion 97 and a pair of end discs 99. As has previously been mentioned, the central portion 97 of the insulating body 39 is provided with a vertical opening 101 for accommodating the operating rod 41. The core member 90 is also provided with a vertical opening aligned with the opening 101 for receiving the operating rod 41, the vertical insulating sleeve 42 being mounted in the opening in the core 90 for insulating the rod 41 from the core. The two windings 93 are wound upon the hub portion 95 of the body 39 on opposite sides of the central portion 97 and between the end discs 99.

The two pole pieces 91 are of inverted L-shape and extend downwardly on opposite sides of the contacts 33 and 35, and are secured to the opposite ends of the core 90 outside the discs 99. The lower ends of the pole pieces 91 are centrally notched, as indicated at 103, in Figs. 1 and 2, to provide a pair of pole shoes 105 on the opposite side of each stationary contact 33 and the path of movement of the contact portions of the movable bridging contact 35. This structure of the lower end of the pole pieces concentrates and increases the flux density across the interrupting gaps so as to increase the force which acts to move the arcs outwardly. The angular extensions 92 of the upper ends of the pole pieces 91 form pole shoes for cooperating with the lower end of the magnetic plate 81 of the trip member 19 so as to attract the same and move the trip member in a counter-clockwise direction as viewed in Fig. 2 when a high magnitude overload or short circuit condition occurs in the circuit controlled by the breaker to trip the breaker.

The blowout action of the electromagnetic means is briefly as follows. The current flows in opposite directions in the two arcs drawn between the stationary contacts 33 and the movable contact 35, and since the magnetic fields between the two pairs of pole shoes 105 are in the same direction across the arc path, the arcs are moved in opposite directions away from one another by the magnetic fields.

It will also be noted that the path taken by the current during circuit interruption is substantially U-shaped, due to the structure of the contacts, so that the magnetic field produced by the current flow through this path also tends to move the two arcs outwardly in opposite directions from one another.

It will be observed from Fig. 8 that the windings 93 are each separately connected to one of the stationary contacts 33 so that the two gaps

are located between the windings 93. The end of one of the windings 93 is adapted to be connected to one of the end terminals of the breaker, while the end of the other winding 93 is adapted to be connected in series circuit with the thermally responsive bimetallic trip element 23 and to the opposite end terminal of the breaker through suitable connecting means.

The operation of the circuit breaker as thus far described is briefly as follows. With the breaker in the closed position as shown in Figs. 2 and 11, let it be assumed that it is desired to manually open the contact means. The operating handle 53 is moved in a counter-clockwise direction about its pivot axis 47. When the lost motion between the operating handle and the toggle link 55 is taken up by this movement, that is, when the lower edge of the slot 71 engages the transverse pin 69, the continued movement of the operating handle causes rotation of the upper toggle link 55 in a counter-clockwise direction about the pivot axis 47 to effect a collapse of the toggle links 56 and 57. As soon as the knee pivot pin 73 of the toggle crosses the line joining the pivot axis 47 and the pivot pin 77, the force exerted by the opening spring 49 acts through levers 45 and 59 to quickly move the toggle links to their collapsed position independently of the movement of the operating handle. The movement of the toggle links to the collapsed position as shown in Fig. 10 effects a counter-clockwise movement of the bell crank levers 59 about their pivot axes 75 from the position shown in Fig. 11 to the position shown in Fig. 10. This movement of the bell crank levers 59 allows the trip latch member 19 to be moved downwardly in the slots 81 to permit downward movement of the lever 45 and operating rod 41 under the biasing influence of the opening spring 49. Downward movement of the operating rod 41 under the influence of the spring 49 moves the movable bridging contact 35 to the open-circuit position, as shown in Fig. 10. It will be noted that in this position of the parts the trip latch member 19 still connects the actuating means with the contact lever 45 and operating rod 41.

To manually close the contact means of the breaker the operating handle 53 is moved in a clockwise direction about its pivot axis 47. Since the transverse pin 69 is in engagement with the upper end of the slot 71 in the operating handle, this movement of the operating handle causes clockwise rotation of the upper toggle link 55 to effect movement of the toggle links 56 and 57 from their collapsed positions, as shown in Fig. 2, to their extended or overset position against a stop, shown in Fig. 11. The movement of the toggle links from collapsed to extended position by the operating handle 53 causes the contact pressure spring 61 to move the bell crank levers 59 in a clockwise direction about their pivot axes 75. This clockwise movement of the bell crank levers moves the trip latch member 19 upwardly in its guide slots 81, and since the free end of the contact lever 45 engages the latch plate 85 of the trip latch member, the contact lever 45 and the operating rod 41, which carries the movable bridging contact 35, are moved upwardly to effect closing of the contact means. It will be noted that in the closed position of the breaker, as shown in Figs. 2 and 11, the toggle links 55 and 57 are overset and held against further movement by a suitable stop means so that the breaker is maintained in closed circuit position. The contact pressure spring 61 exerts a downward force on the transverse con-

necting pin 17 carried by the bell crank lever 59, and this force is transmitted to the movable bridging contact 35 through the agency of the trip latch member 19, contact lever 45 and operating rod 41 to effect a pressure engagement of the movable bridging contact 35 with the stationary contacts 33.

If an overload of low magnitude and sufficient duration occurs in the circuit controlled by the breaker, the bimetallic trip element 23 is heated a sufficient amount to flex and move the trip latch member 19 in a counter-clockwise direction about its pivot axis 83. This movement of the trip latch member releases the contact lever 45 or disconnects it from the actuating means of the breaker so as to permit movement of the contact lever 45, operating rod 41 and movable bridging contact 35 to open circuit position under the influence of the opening spring 49, as shown in Fig. 12.

Following the above-described tripping operation, the bell crank levers 59 are moved in a clockwise direction about their pivot axes 75 by the spring 61 until the transverse pin 83 of the trip latch member 19 reaches the upper end of its guide slots 87. This movement of the bell crank levers causes a breaking of the toggle links 55 and 57 and the force exerted by the contact pressure spring 61 then moves the toggle links toward collapsed position to reset the trip latch member 19 into operative or latching engagement with the contact lever 45. This movement may be aided by the mass of the latch member 19 and left-hand arms of the bell crank levers 59 or by a light spring (not shown) acting on the bell crank levers 59 to move them counter-clockwise. The parts of the breaker are now in the position shown in Fig. 10 and are ready for a subsequent manual closing operation.

If a high magnitude overload or short-circuit condition occurs in the circuit controlled by the breaker, the lower end of the armature portion 81 of the trip latch member 19 is moved to attracted position against the pole shoes 92 by the pull of the electromagnetic means to effect counter-clockwise movement of the trip latch member 19 about its pivot axis 83. This movement of the trip latch member by the electromagnetic means effects release of the contact lever 45, or disconnection of that member from the actuating means to permit the opening spring 49 to open the contacts in the manner previously described in connection with a thermal tripping operation. Following the magnetic tripping operation, the parts of the breaker are automatically reset in the manner previously described so that the breaker is ready for a subsequent manual closing operation.

An important advantage of the previously described structure is that it provides a considerable decrease in the total time required for circuit interruption over the time required by the prior art structures. This results from the fact that the actuation of the tripping member in response to an overload condition effects immediate disconnection of the actuating means and contact pressure securing means from the contact means. It will be noted that the electromagnetic means 21 and the trip latch member 19 are disposed between the side walls of the frame 25, whereas the actuating means 17 and contact means are located principally outside of the confines of the frame. This provides a very desirable feature since it permits ready access to be had to the actuating means and contact means.

The base 27 of the circuit breaker is of ceramic insulating material and is provided with recesses at each end for accommodating the end terminal bolts 107, which are secured in the base by the fastening nuts 115. If desired, the base may be composed of molded insulating material instead of ceramic material. The terminal bolts 107, together with the cooperating terminal nuts 109, form a means for mounting terminal lugs 111, as shown in Fig. 2; or to connect switchboard studs 113 to the breaker, as shown in Figs. 1 and 4. The inner ends of the terminal lugs 111 are bifurcated, as indicated in Fig. 2, to engage the bolts 107, and are adapted to be secured firmly against the fastening nuts 115, by means of the terminal nuts 109.

In the case of the switchboard studs 113, their upper ends are flattened and bent angularly as shown in Fig. 4. The angularly-bent portions 117 are perforated for engaging the bolts 107 and are firmly clamped against the fastening nuts 115 by means of the terminal nuts 109. It will thus be seen that the terminal structure of the circuit breaker lends itself readily to either of the two types of connections for connecting the breaker in an external circuit.

The base 27 of the breaker is provided with a relatively deep main recess 119 (Fig. 5), the central portion of which forms an interrupting chamber for the contact means as shown in Fig. 2. The base 27 is also provided with a pair of pole shoe receiving recesses 121 disposed on opposite sides of the central portion of the main recess 119 and separated therefrom. The recesses 121 serve to receive the pole shoes 105 of the electromagnetic means, as best shown in Fig. 4.

The previously described breaker unit assemblage is adapted to be removably mounted on the base 27 so that the contact means is disposed in the main interrupting recess or chamber 119 and the pole shoes 105 in the pole receiving recesses 121. For securing the breaker unit assemblage in mounted position on the base 27, there are provided a pair of bolts 123 (Figs. 1 and 4) which extend upwardly through suitable openings provided therefor in the base member. The upper ends of the bolts 123 extend through suitable restricted openings 125 provided therefor in the pole pieces 91 between the pole shoes 105. Recesses 127 are provided in the pole pieces 91 for receiving fastening nuts 129 into which the bolts 123 are screwed. The recesses 127 may be of irregular or square shape so as to prevent the fastening nuts 129 from turning when the screws 123 are turned. It will thus be seen that it is a relatively simple matter to remove the unitary breaker assemblage from the base 27 for adjustment or repair purposes.

Suitable closure plates 131 (Fig. 2) are provided for closing the open side of the interrupting chamber 119. The plates 131 are secured to the unitary breaker assemblage by means of the bolts 37 and the stationary contacts 33, so that when the unitary breaker assemblage is mounted in position on the base 27 the plates 131 serve to close the interrupting chamber. The plates 131 are provided with a suitable opening for receiving the operating rod 41 and this opening is substantially closed to the passage of gases generated in the interrupting chamber by means of the spacer sleeve 51, the opening spring 49 and the electromagnetic core 90.

The provision of the closed chamber about the contact means of the breaker aids in extinguishing the arc drawn between the contacts during

circuit interruption, the pressure developed by the arc tending to quench the same.

- Additional arc-extinguishing means are provided in the chamber 119. The additional arc-extinguishing means comprises a plurality of spaced and insulated arc-extinguishing plates 133 disposed in the opposite ends of the interrupting chamber 119. These plates may be of metal or other suitable type of arc-extinguishing material. The electromagnetic means 21 moves the arcs drawn between the stationary contacts 33 and the movable bridging contact 35 in opposite directions into the spaces between the plates 133 to split the arcs up into a series of short arcs which are quickly cooled and extinguished by the arc-extinguishing plates 133.

Additional recesses or chambers 135 (Fig. 5) are provided opposite the ends of the arc-extinguishing plates 133 and these chambers are open to the main interrupting chamber 119 through the spaces between the plates. Since these chambers 135 are closed or substantially closed, the air or gas within the same is compressed during circuit interruption by the rise in pressure within the main interrupting chamber 119, so that the arc and hot gases are caused to penetrate deeply within the spaces between the arc-extinguishing plates 133 and are maintained therein until the arc is extinguished. Where extremely large amounts of power are required to be interrupted it may be expedient to provide vents or openings to allow escape of the gas from the interrupting chamber. In such cases the vents or openings would be positioned at and joining the chambers 135 so that the gases would be required to first pass by the arc-extinguishing plates 133, where they would be considerably cooled before exit.

The provision of the interrupting chamber within the base of the circuit breaker considerably reduces the overall size of the breaker and eliminates the necessity of any additional arc chamber structure.

A modification of the invention is illustrated in Fig. 9. This modified form of circuit breaker comprises a stationary contact 137, a cooperating movable contact 139 secured to the free end of a switch arm 141 which is pivotally mounted at its opposite end to a fixed support by means of a pivot pin 143. An opening spring 145 is provided for biasing and moving the switch arm 141 to open circuit position. The actuating means for the switch arm comprises a toggle type operating handle 147 eccentrically pivoted about a fixed axis 149, a toggle link 151 pivotally connected at its upper end to the lower portion of the handle 147 by means of a pivot pin 153, and pivoted at its lower end to the free end of a contact pressure securing spring 155 by means of a pivot pin 157. The opposite end of the spring 155 is pivotally mounted on a fixed pivot pin 159. The spring 155, and through it the actuating means of the breaker, is releasably connected to the switch arm 141 by means of a trip latch member 161, which is pivotally secured to the mid-portion of the spring 155 at its upper end. The lower end of the trip latch member 161 is provided with a latch face 163 for normally engaging a latch pin 165 secured to the switch arm 141. An electromagnetic means 167 is provided for actuating the trip latch member 161 to its released position to disconnect the switch arm 141 from the actuating means and from the contact pressure securing spring 155, the electromagnetic means 167 being provided

with a movable plunger 169 for engaging and moving the trip latch member 161.

The operation of this form of the invention is briefly as follows. To open the contact means 137 and 139, the operating handle 147 is moved in a counterclockwise direction, as viewed in Fig. 9. This movement of the operating handle effects collapse of the toggle formed by the lower portion of the handle 147 and the link 151. The collapse of this toggle allows the switch arm 141 to be moved to open-circuit position under the influence of the opening spring 145. To close the contact means 137 and 139 the operating handle 147 is moved in a clockwise direction about its pivot axis 148 to effect movement of the toggle formed by the lower portion of the handle and the link 151 to the over-set or made position as shown in Fig. 9. This movement of the toggle to the over-set position effects clockwise movement of the spring 155 about its pivot axis 159 and downward movement of the trip latch member 161 to cause movement of the switch member 141 to closed circuit position. The resiliency of the spring 155 provides the necessary contact pressure between the stationary contact 137 and the movable contact 139.

When the electromagnet 167 is energized a sufficient amount, the plunger engages and moves the trip latch member 161 in a counter-clockwise direction to effect a disconnection of the switch arm 141 from the actuating means and the contact pressure securing spring 155 to permit the switch arm to be moved to its open position under the influence of the opening spring 145. This form of the invention possesses the same desirable advantage as described in connection with the original embodiment, namely, a decrease in the overall time required for circuit interruption. This results from the fact that the trip means is operable to effect immediate disconnection of the switch arm or movable contact from both the actuating means and the contact pressure securing means.

While the invention has been disclosed in accordance with the provisions of the patent statutes, it is to be understood that various changes in the structural details may be made without departing from the spirit of the invention. It is desired, therefore, that the appended claims be given the broadest reasonable construction possible in the light of the prior art.

I claim as my invention:

1. In a circuit breaker, a stationary contact, a cooperating contact movable to open and to closed position, means biasing said movable contact to open position, actuating means for effecting movement of the movable contact to open and to closed position, means for securing a pressure engagement of said contacts in the closed position of said movable contact, and trip means operable to immediately release said contacts from said contact pressure securing means and said actuating means to cause opening of said contacts independently of the influence of said actuating means and said contact pressure securing means.

2. In a circuit interrupter, a pair of rigidly mounted separable contacts, an operating member, connecting means for moving one of said contacts upon movement of said operating member, means applying a biasing force to said connecting means adjacent said movable contact for moving it to open position, means applying a biasing force to said connecting means remote from said movable contact for supplying contact pressure, and electro-responsive releasable means

said connecting means intermediate said two biasing means.

3. In a circuit breaker, relatively movable contacts, a switch member movable to open and to closed position to open and to close said contacts, means biasing said switch member to open position to quickly open said contacts, actuating means for moving the switch member to open and to closed position including a toggle and a 10 means for securing pressure engagement of the contacts in the closed position of the contacts, trip means for immediately freeing said switch member from the influence of said actuating means and pressure securing means to cause separation and opening of said contacts independently of the position of said actuating means and pressure securing means.

4. In a circuit breaker, a fixed contact, a cooperating movable contact movable to open and 20 to closed position, means biasing said movable contact to open position, actuating means for moving said movable contact to open and to closed position including a spring means for securing a pressure engagement of said contacts 25 in the closed position of said movable contact, trip means for freeing said movable contact from the influence of said actuating means and from said spring means to permit movement of said movable contact to open position independently 30 of the influence of said actuating means and spring means.

5. In a circuit breaker, a fixed contact and a cooperating movable contact movable to open and to closed position, means biasing said movable contact to open position, actuating means for moving said movable contact to open and to closed position including a spring means for securing a pressure engagement between said contacts in the closed position of said movable contact, a latch member normally and releasably effecting operative connection of said actuating means and spring means to said movable contact, and trip means for moving said latch member to release said movable contact from its operative connection to said actuating means and said spring means.

6. In a circuit breaker, a fixed contact and a cooperating movable contact movable to open and to closed position, means biasing said movable contact to open position, actuating means for moving said movable contact to open and to closed position including a spring means for securing a pressure engagement between said contacts in the closed position of said movable contact, a latch member normally and releasably effecting operative connection of said actuating means and spring means to said movable contact, and electroresponsive trip means operable in response to predetermined conditions for moving said latch member to release said movable contact from its operative connection to said actuating means and said spring means.

7. In a circuit breaker, relatively movable contacts, a switch member movable to open and to closed position to open and to close said contacts, means biasing said switch member to open position to open said contacts, actuating means for effecting movement of the switch member to open and to closed position including a spring means for securing a pressure engagement of said contacts in the closed position of the switch member, and means normally effecting an operative connection of said actuating means and spring means to the switch member including a latch member movable from a normal connecting

position to a released position to release said switch member from operative connection to said actuating means and pressure securing means to permit opening of the switch member by its biasing means free from any influence of said actuating means and pressure securing means. 5

8. In a circuit breaker, relatively movable contacts, a switch member movable to open and to closed position to open and to close said contacts, means biasing said switch member to open 10 position, actuating means for effecting movement of the switch member to open and to closed position including a toggle, and a spring means for connection to said switch member, said spring means providing a pressure engagement of said 15 contacts when the breaker is closed, and a releasable latch member normally effecting an operative connection of said toggle and spring means to said switch member, said latch member being movable to release said switch member 20 from operative connection to said spring means to permit opening of the switch member by its biasing means free of any influence by said spring means and toggle.

9. In a circuit breaker, relatively movable contacts, a switch member movable to open and to closed position to open and to close said contacts, means biasing said switch member to open position, actuating means for effecting movement of the switch member to open and to closed 25 position including a toggle and a spring means for connection to said switch member, said spring means providing a pressure engagement of said contacts when the breaker is closed, and a releasable latch member normally effecting an operative connection of said toggle and spring 30 means to said switch member, said latch member being movable to release said switch member from operative connection to said toggle and spring means to permit opening of the switch 35 member by its biasing means free of any influence by said spring means and toggle, said latch member being bodily shiftable by said actuating means during normal operation of said breaker.

10. In a circuit breaker, relatively movable contacts, a switch member movable to open and to closed position to open and to close said contacts, means biasing said switch member to open position, actuating means for effecting movement of the switch member to open and to closed 40 position including a toggle and a spring means for connection to said switch member, said spring means providing a pressure engagement of said contacts when the breaker is closed, and a releasable latch member normally effecting an operative connection of said spring means to said 45 switch member, said latch member being movable to disconnect said toggle and spring means from said switch member to permit opening of the switch member by its biasing means free of any influence by said spring means and toggle, said latch member being bodily shiftable by said actuating means during normal operation of said breaker, and current responsive means operable 50 in response to predetermined conditions to move 55 said latch member to effect opening of the switch member.

11. In a circuit breaker, a base, relatively movable contacts, actuating means manually operable to open and close said contacts, trip means 60 operable to cause opening of said contacts including an electromagnet, said electromagnet being provided with pole pieces adjacent said contacts for aiding in extinguishing the arc formed during circuit interruption, a frame for 65 70

- supporting said contacts and said actuating means and said trip means to form a unit, means for removably mounting said unit on said base, said base being provided with a recess forming an interrupting chamber for receiving said contacts and pole pieces, and closure means for closing the interrupting chamber.
5. 12. In a circuit breaker, a base, relatively movable contacts, actuating means manually operable to open and close said contacts, trip means 10 operable to cause opening of said contacts including an electromagnet, said electromagnet being provided with pole pieces adjacent said contacts for aiding in extinguishing the arc formed during circuit interruption, a frame for supporting said contacts and said actuating means and said trip means to form a unit, means for removably mounting said unit on said base, said base being provided with a recess forming an 15 interrupting chamber for receiving said contacts and pole pieces; and a closure means carried by said unit for covering said interrupting chamber when the unit is in mounted position.
13. In a circuit breaker, a fixed contact and a cooperating movable contact movable to open 20 and to closed position, means biasing said movable contact to open position, actuating means for moving said movable contact to open and to closed position including a spring means for 25 securing a pressure engagement between said contacts in the closed position of said movable contact, a latch member normally and releasably effecting an operative connection of said actuating means and spring means to said movable contact, an electromagnetic and a thermally responsive trip means, each operable in response to predetermined conditions to move 30 said latch member to release said movable contact from operative connection to said actuating means and said spring means.
40. 14. In a circuit breaker, a base of insulating material provided with a recess forming an interrupting chamber, relatively movable contacts disposed in said chamber, actuating means for said contacts mounted on said base outside said 45 chamber, means closing the open side of said chamber, a plurality of spaced and insulated arc-extinguishing plates disposed in said chamber, and means for moving the arc drawn between said contacts during circuit interruption 50 into said plates to extinguish the same, said base being provided with at least one auxiliary chamber disposed opposite said plates and joining the interrupting chamber through the spaces between the plates for providing a back pressure 55 to cause the arc to penetrate deep into the spaces between the plates and remain there until extinguished.
55. 15. In an air circuit breaker, a pair of spaced stationary contacts and a cooperating movable 60
- bridging contact, means forming a relatively small closed pressure chamber about said contacts, a plurality of spaced arc-extinguishing plates disposed in said chamber adjacent each stationary contact means for moving the arcs drawn between said bridging contact and the stationary contacts in opposite directions into said plates for extinguishing the same, and means for actuating said bridging contact from outside said chamber.
10. 16. In a circuit breaker, a base of insulating material therefor provided with a recess forming an interrupting chamber, a breaker unit including a pair of spaced stationary contacts, a movable bridging contact, actuating means for the bridging contact, electromagnetic means having a pair of pole pieces disposed on opposite sides of the contacts and path of movement of the bridging contact for moving the arcs drawn between said bridging contact and stationary 15 contacts outwardly in opposite directions, means removably mounting said breaker unit on said base so that said contact means and pole pieces are disposed in said recess, means closing said interrupting chamber, and a plurality of spaced 20 and insulated arc-extinguishing plates disposed in said chamber adjacent each stationary contact into which the arcs are moved by said electromagnetic means.
17. In a circuit breaker, a fixed contact and 30 a cooperating movable contact movable to open and to closed circuit position, means biasing said movable contact to open circuit position, actuating means normally connected to said movable contact for moving said movable contact to open 35 and closed circuit position including resilient means for securing a pressure engagement between said contacts in the closed position of said movable contact, trip means for disconnecting said actuating means and said resilient contact 40 pressure securing means from said movable contact to permit said biasing means to quickly move said movable contact to open circuit position.
18. In a circuit breaker, a fixed stationary 45 contact, a cooperating contact movable to open and to closed circuit position, means biasing said movable contact to open circuit position, actuating means for effecting movement of said movable contact to open and to closed circuit 50 position including a means for securing a pressure engagement of said contacts in the closed circuit position of said movable contact, and trip means operable to immediately render said 55 actuating means and contact pressure securing means incapable of exerting any force on said movable contact opposing movement thereof to open position by its biasing means.
